US00D849345S

(12) **United States Design Patent** (10) Patent No.: **US D849,345 S**
Thorne et al. (45) Date of Patent: **** May 21, 2019**

(54) **ROLLER CLEANING UNIT**

- (71) Applicant: **SHARKNINJA OPERATING LLC**,
Newton, MA (US)
- (72) Inventors: **Jason B. Thorne**, Wellesley Hills, MA
(US); **Yao Ming**, Newton, MA (US);
Daniel R. Der Marderosian,
Westwood, MA (US); **Daniel Meyer**,
Boston, MA (US); **Patrick Clearly**,
Allston, MA (US); **Gordon Howes**,
Suzhou (CN); **David Wu**, Newton, MA
(US); **Nancy Gao Wenxiu**, Suzhou
(CN)
- (73) Assignee: **SharkNinja Operating LLC**,
Needham, MA (US)
- (**) Term: **15 Years**
- (21) Appl. No.: **29/601,158**
- (22) Filed: **Apr. 19, 2017**

(57) **CLAIM**

The ornamental design of a roller cleaning unit, as shown
and described.

DESCRIPTION

FIG. 1 is a front, right perspective view of a roller cleaning
unit showing our new design;

FIG. 2 is a front view thereof;

FIG. 3 is a left, front perspective view thereof;

FIG. 4 is a bottom view thereof;

FIG. 5 is a right, bottom perspective view thereof;

FIG. 6 is a left, bottom perspective view thereof; and,

FIG. 7 is a right side view thereof.

The broken lines are included for the purpose of illustrating
the unclaimed portions of the article and form no part of the
claim.

1 Claim, 7 Drawing Sheets
